UNITED STATES PATENT OFFICE.

PROCTOR P. COOLEY, OF PEORIA, ILLINOIS, ASSIGNOR TO CULTER & PROCTOR STOVE CO.,
OF PEORIA, ILLINOIS, A CORPORATION OF ILLINOIS.

STOVE.

1,272,387.

Specification of Letters Patent.

Patented July 16, 1918.

Application filed January 12, 1914. Serial No. 811,652.

To all whom it may concern:

Be it known that I, PROCTOR P. COOLEY, a citizen of the United States, a resident of Peoria, in the county of Peoria and State of Illinois, have invented new and useful Improvements in Stoves, of which the following is a specification.

This invention relates to improvements in stoves and has for its object the provision of a stove having an upper and lower oven in which roasting and baking may be carried on at the same time, the flue system being so arranged as to obtain maximum efficiency.

15 A further object is the provision of a ventilating oven whereby the temperature thereof may be regulated, as desired.

20 A further object is the provision of permanent ash chutes in the ash-pit so that all of the ashes are discharged into the ash-pan.

25 A further object is the improvement in various details and construction, making a stove constructed according to my invention, a desirable and useful article in the household.

To the accomplishment of the foregoing and such other objects as may hereinafter appear, my invention consists in the combination, construction and arrangement of parts hereinafter described, and then sought to be defined in the appended claim, reference being had to the accompanying drawings forming a part hereof, and which shows 35 merely for the purpose of illustrative disclosure, a preferred embodiment of my invention, it being understood that various changes may be made in practice within the scope of the claim, without digressing from 40 my inventive idea.

In the drawings:—

Figure 1 represents a vertical transverse section taken on the line 1—1 of Fig. 2;

Fig. 2 is a vertical longitudinal section 45 taken substantially on the line 2—2 of Fig. 1;

Fig. 3 is a vertical transverse section taken substantially on the line 3—3 of Fig. 2;

Fig. 4 is a perspective view of a detail.

50 Referring now to the drawings, in which Figs. 1 to 3 represent one form of my invention, the numeral 1 designates the fire-pot of the stove, 2 the ash-pit, 3 the top, 4 the upper oven and 5 the lower oven. The

rear wall 6 of both ovens is practically continuous, being spaced from the rear wall 7 of the stove to provide a downward continuation 8 of the flue 9. The bottom member 9' of the lower oven is spaced from the bottom of the stove 10 to provide a horizontal flue 11, and the front wall or member 12 of said lower oven 5 is spaced from the inner wall of the ash-pit 2 so as to provide the upwardly extending flue 12'. This flue communicates with the flue 13, provided by the bottom member 14 of upper oven 4 and top member 15 of lower oven 5, which are spaced apart as shown. The hood 16 communicates with this flue 13 at the rear of the stove and is adapted to receive the ordinary stove-pipe, 70 not shown. The baffle-plate 17 is shown extending diagonally across said flue 13 so as to cause the products of combustion to circulate between the two ovens and not to be discharged directly into the chimney. In 75 this construction, the products of combustion pass over and behind the upper oven and then practically all around the lower oven, finally passing beneath the upper oven until discharged. It is therefore seen that 80 both the upper and lower ovens are subject to heat on all sides, so that baking and roasting may be carried on at the same time in both ovens.

Other objects of my invention include an 85 improved means of ventilating one of the ovens, particularly the upper oven. The rear wall of the upper oven is perforated as at 25, over which perforations is placed the hood or guard 26. This prevents soot 90 from being forced down into the oven. A suitably controlled opening is provided in the front door, whereby the admission of air may be regulated. It is therefore seen that cool air may be admitted to the oven, as desired, so as to properly regulate the temperature therein. The plurality of integral projections 28 in the top of the upper oven provide means for retarding the radiation of the heat so as to prevent burning of the material in the oven, and tending to provide a more uniform distribution of the heat.

I also provide an important improvement in stoves, in the permanent ash chutes, which are formed by providing the inwardly inclined portions 28' in the side of the stove, the side of the oven and the end of the stove and the door, so that ashes dropping from

the grate, will be discharged directly into the ash-pan 29 and not fall between the ash-pan and the walls of the ash-pit, as usual.

This stove provides a straight front so that 5 a contact reservoir 30 may be applied thereon so that water may be readily heated for culinary purposes. The door 31 is provided on the front of the stove so that it may be supplied with fuel from the front 10 instead of from the side, as is usual. Clean-out openings are provided so that the flues may be readily cleaned.

It is seen therefore, that a stove constructed according to my invention, includes 15 many details of practical value, the principal one being the circulation of the products of combustion about both ovens so as to utilize the heat of the products of combustion to a maximum degree.

20 There is no necessity of using an additional heater or heating element of any sort to obtain the requisite degree of temperature in both ovens, the arrangement of flues being such that the lower oven is heated sufficiently.

Any soot that may be forced through the apertures 25 will collect in the guard 26 and

will not pass into the oven to spoil or injure any of the contents thereof. The ventilating feature provides means whereby the over-heating of the oven may be prevented and the baking or roasting odors discharged into the discharge flue.

30 What I claim is:—

A stove having a fire-box and underlying 35 ash-pit on one side, a continuous and uninterrupted vertical flue on the opposite side, a pair of intervening, vertically spaced ovens, the upper oven being next to the fire box and spaced from the top of the stove to provide 40 a connecting passage between said flue and fire-box, the lower oven being spaced from the ash-pit and the bottom of the stove to provide a connecting passage between the flue and the space between the ovens, the 45 ovens being connected adjacent the flue to cause the heated gases to pass around the lower oven before coming into contact with the under side of the upper oven, and an outlet for the space between the ovens.

PROCTOR P. COOLEY.
